(21) Appl. No.: **29/157,013**

The ornamental design for a plug socket for a radio telephone handset, as shown and described.

(22) Filed: **Mar. 12, 2002**

DESCRIPTION

(30) **Foreign Application Priority Data**

Oct. 30, 2001 (WO) DM/057 914

FIG. 1 is a front, top and right side perspective view of a plug socket for a radio telephone handset;

(51) LOC (7) Cl. **14-03**

FIG. 2 is a left side elevation view of a plug socket for a radio telephone handset of FIG. 1;

(52) U.S. Cl. **D14/240**

FIG. 3 is a right side elevation view of a plug socket for a radio telephone handset of FIG. 1;

(58) Field of Search **D14/240-256**

FIG. 4 is a bottom plan view of a plug socket for a radio telephone handset of FIG. 1;

D14/433, 356, 438, 357; D13/152, 160,

161, 164, 178, 173, 133, 154, 137.1, 123;

439/651, 571; 379/419, 420, 428, 440,

93.01, 93.28; 455/901, 462, 77, 575; 375/220-225

FIG. 5 is a top plan view of a plug socket for a radio telephone handset of FIG. 1; and,

(56) **References Cited**

FIG. 6 is a rear elevation view of a plug socket for a radio telephone handset of FIG. 1.
